UNITED STATES PATENT OFFICE.

J EMIL DRYFOOS, OF NEW YORK, N. Y.

DESIGN FOR AN AUCTION-BRIDGE SCORE BOOK.

Application filed March 12, 1923. Serial No. 5,452. Term of patent 3½ years.

To all whom it may concern:

Be it known that I, J EMIL DRYFOOS, a citizen of the United States, residing at New York, in the county of New York and State of New York, have invented a new, original, and ornamental Design for Auction-Bridge Score Book, of which the following is a specification, reference being had to the accompanying drawing, forming part thereof.

The figure is a perspective outside view of an auction bridge score book, showing my new design.

What I claim is:—

The ornamental design for an auction bridge score book as shown.

In testimony whereof I have affixed my signature.

J EMIL DRYFOOS.
